(57) **CLAIM**

The ornamental design for a display screen with graphical user interface for flight risk prediction, as shown and described.

DESCRIPTION

FIG. 1 is a front view of a display screen with graphical user interface for flight risk prediction showing our new design; FIG. 2 is a front view of a second embodiment of a display screen with graphical user interface for flight risk prediction; and,

FIG. 3 is a front view of a third embodiment of a display screen with graphical user interface for flight risk prediction. The broken lines showing a display screen illustrate portions of the article, and form no basis of the claimed design.
